UNITED STATES PATENT OFFICE.

EDGAR P. HAZAER, OF DETROIT, MICHIGAN, ASSIGNOR TO AMERICAN BLOWER COMPANY, OF DETROIT, MICHIGAN, A CORPORATION OF NEW YORK

SWITCHING MECHANISM FOR CONTROLLING CIRCUITS.

1,404,694.

Specification of Letters Patent. Patented Jan. 24, 1932.

Application filed November 28, 1916. Serial No. 133,917.

To all whom it may concern:

Be it known that I, EDGAR P. HAZAER, citizen of the United States, residing at Detroit, in the county of Wayne and State of Michigan, have invented certain new and useful Improvements in Switching Mechanism for Controlling Circuits, of which the following is a specification, reference being had therein to the accompanying drawing.

10 This invention relates to switch mechanism for controlling circuits, and while susceptible of a variety of adaptations, is designed more particularly for use in connection with motor driven fans of a reversible type, and wherein the movement of the motor may, as occasion demands, be reversed in order to reverse the movement of the fan without any injurious effect upon the motor.

20 It is often times desirable to reverse the movement of motor driven ventilating fans, whereby a fan ordinarily employed as a blower adapted to exhaust air or the like from a building, etc., may be converted into a suction creating medium to draw air into the building, and as will be appreciated by those skilled in the art, it is exceedingly dangerous, if not disastrous to the motor for a careless or inexperienced operator to suddenly reverse the same without permitting it to come to a stop.

It may therefore be said to be one of the primary objects of the present invention to provide a time reversing switch, that is to say, a reversing switch having operatively associated therewith time controlled mechanism constructed and arranged whereby as the switch is moved into a position to break the circuit, the time mechanism is set into operation to prevent the immediate closing of the circuit upon the further movement of the switch to circuit closing position.

It is a further object of the invention to provide in operative association with a motor or the like, a suitable circuit controlling switch and clock mechanism operating to prevent the closing of the circuit after the switch has moved to circuit closing position until a sufficient interval of time has elapsed to allow the motor to come to a stop.

Again the invention includes a manually operated reversing switch for motor driven fans or the like, and operatively associated mechanism automatically operating, as the

switch is moved at the will of the operator into motor reversing position, to prevent the closing of the circuit until after the expiration of a predetermined interval of time.

Further, the invention embodies a reversing switch mechanism and a time controlled magnetic switch, the latter operating to close the circuit only after the first mentioned switch mechanism has been maintained in circuit reversing position for a predetermined interval.

The invention also embodies means whereby the lapse of time between the circuit closing movement of the operating switch and the actual closing of the circuit may be readily regulated at will.

More particularly the invention includes a reversing switch operatively associated with a fan motor or the like, electrical connections between the switch and motor, and an auxiliary time controlled switch, the latter operating to maintain the circuit open when the operating switch is moved into reversing position, for an interval of time and subsequently operating to automatically close the circuit, the parts being constructed and arranged with a view to simplicity in design and construction, efficiency in operation and durability in use.

The present invention is not to be confused with that type of apparatus generally known as time switches, and wherein, at regular intervals of time a switch is opened or closed, but has to deal more particularly with a timing mechanism interposed in the switching mechanism whereby as the switch is opened whenever desired by the operator, the current is broken and whereby as the switch is again closed, a sufficient interval of time must thereafter elapse before the closing of the circuit.

In the present embodiment of the invention, I have, for the purpose of illustration, shown the time reversing switch applied to a series wound motor, though it is to be understood that by simple changes in the design of switch and associated parts, the appliance is clearly applicable to a shunt, compound, three phase or certain single phase motors, and it is to be further borne in mind that while the motor is shown and described as applied to a ventilating fan or the like, the invention in its broader aspect is not to be construed as limited to

this specific application but may be found to be quite useful and satisfactory for other than motor work and other than fan work.

In the drawings:—

5 Figure 1 is a front elevation of a base board with my improvements applied thereto. Figure 2 is a side elevation, parts being shown in section.

10 Fig. 3 is a diagrammatic view illustrating more particularly the circuits.

With more particular reference to the drawings, wherein like reference numerals refer to corresponding parts throughout the several views, a suitable standard double 15 throw or reversing switch is provided, the same being preferably manually operable and having an operating handle 1 and knife blades 2, 3 and 4 respectively. The blades are pivoted at 2^a, 3^a, and 4^a respectively to 20 suitable contact members 5, 6, and 7, mounted upon a supporting base board A of any desired construction. Arranged to one side of the contact members 5, 6, and 7 are a series of contact members 8, 9 and 10, and arranged to the opposite side of said first mentioned contact members are contact members 11, 12 and 13.

25 The contact members just referred to are adapted to have suitable electric connection, to be hereinafter more particularly described, with the member to be operated. This member in the embodiment of the invention illustrated takes the form of a motor or the like 14, the motor preferably being 30 that type known as a series wound motor, though in this connection it is to be borne in mind that the motor may take various forms and designs and it is also to be borne in mind that the mechanism herein contemplated is applicable to uses other than in 35 connection with motors.

40 The electric connections are such that when the manually operable switch is moved into operative contact with the contact members 8, 9 and 10 respectively, the motor will be driven in one direction, whereas when the switch is moved about its pivotal support into engagement with the contact members 11, 12 and 13, the movement of the 45 motor will be reversed.

45 The motor is illustrated as having operatively associated therewith for movement thereby a ventilating fan 15 generally known as a disk or wall type fan, primarily intended to exhaust air, steam, smoke, gases or the like out of buildings, and it is one of the primary objects of the invention to provide novel means whereby the action of the motor and fan may be reversed without injurious affect upon the motor whereby to 50 adapt the fan for blowing or drawing air into the building as desired.

55 It is a matter of common knowledge in the art to which the invention relates that there should an ignorant or inexperienced opera-

tor quickly reverse the switching mechanism as ordinarily constructed, without allowing sufficient interval to elapse to permit the motor to stop, this action will result in burning and quick destruction of the motor. Therefore, I have provided means for overcoming 70 this objection, the said means preferably taking the form of a time controlled element operatively associated with the switching mechanism, whereby upon the movement of 75 the switch into position to reverse the movement of the motor, the circuit will not be closed and the motor will not be reversed until after a predetermined interval has elapsed, such interval being determined by 80 the time necessary to permit the motor to first slow down or come to a full stop.

85 In carrying out this feature of the invention, there is provided an automatic time control switch, the same including a solenoid magnet 16, preferably arranged vertically and having a slideable core 17 adapted to fall by gravity when the circuit is broken and the said core having at the lower edge thereof contact brushes 18 adapted when the core 90 is in elevated position to engage suitable contact members 19. Projecting rearwardly from the core is a suitable guide pin 20 adapted to engage in a suitable guide-way 21 arranged upon the base board A. The downward movement of the solenoid core 17 is governed by an adjustably mounted collar 22. The collar being threaded to the core and held in adjusted positions in any desired manner, and the same being adapted 100 to engage the upper surface of the framework 23, of the magnet switch. The core at the upper end, takes the form of a yieldable rod or wire 24 having a hook end or terminal 25 at the top thereof. The hook end 25 105 of the rod 24 is adapted to operatively engage a suitable clock movement when the solenoid core is allowed to fall in the breaking of the circuit, with the result that the clock mechanism is set into operation and 110 after a predetermined interval of time has elapsed, the circuit will be re-established by the elevation of the solenoid core through the medium of electrical connections with the clock movement.

115 The time control element may take various forms and still be within the spirit of my invention. In that embodiment of the invention herein disclosed, for the purpose of illustration, the time element is applied to 120 a common clock movement, unnecessary to describe in detail, suffice it to say that the main ratchet wheel 26 is mounted upon a suitable shaft 27 upon which is also mounted for rotatable movement therewith an actuating 125 rock arm 29 having suitable weights 30 at opposite ends thereof and an actuating pawl or dog 31 adapted to engage the teeth of the ratchet 26 whereby to exert pressure thereon and set the clock mechanism into 130

play. Mounted upon the arm 29 for movement therewith, is a suitable spring arm 32 having a contact member 33 adapted in one position of the arm 29 to engage a cooperating contact member 34 mounted in fixed position upon the frame of the clock mechanism. A suitable guard 35 overlies one end of the contact member 34 to prevent engagement of the contact member 33 with said member 34 until the member 33 is moved to a point beyond said guard. An adjustably mounted stop 36 is mounted on the framework of the clock mechanism and adapted to engage one end of the weighted rock arm 29 whereby to limit the movement of the latter in one direction. Also mounted upon the weighted arm 29 is a suitable curved spring arm 37 adapted to be engaged by the hooked end 25 of the rod 24 of the solenoid core. The spring arm 37 is adapted to yield laterally under the action of the rod 24 as the same is moved upwardly into contact with the spring arm under the action of the solenoid core in its raising movement upon the closing of the circuit.

The operation of the time controlled mechanism just described may be reviewed as follows:

Assuming that the operator moves the switch through the medium of the handle 1 out of contact with say, the contacts, 8, 9, and 10, the circuit will be broken and the solenoid core will immediately drop by force of gravity whereby to break the connection between the brushes 18 and the stationary contacts 19. In the lowering movement of the solenoid core, the hooked end 25 of the rod 24 will by its engagement with the upper surface of the spring arm 37 of the rock arm 29 exert downward pressure on said spring arm 37 thereby rocking the weighted arm 29 and causing the dog 31 to ride downwardly over a series of the teeth of the ratchet wheel 26. As the weighted end of the rock arm 29 which carries the pawl or dog 31 reaches the limit of its lowering movement, depending upon the position of the stop member 36, the hooked end 25 will by its continued lowering movement become disengaged with the spring arm 37 when, under the action of the weight at the opposite end of the arm 29, the pawl or dog 31 will exert upward pressure on the ratchet wheel 26 thereby starting the clock movement. This latter movement of the arm 29 is a gradual one because of the restraining action of the escapement mechanism of the clock movement. The spring arm 32 moves with the arm 29 in a direction towards and above the contact member 34, but because of the guard 35, the contact member 33 of said spring cannot engage with the contact member 34 until after the contact member 33 has passed over and beyond the guard 35. So soon as the contact member 33 passes beyond the guard 35

the same under the action of the spring 32 will immediately fall into engagement with the contact member 34, thereby energizing the solenoid switch causing the core to elevate and close the circuit at 18-19. It is understood of course that at this time the blades of the operating switch 1 are in contact either with the contacts 8, 9 and 10 or assuming that the motor is to be reversed in engagement with the contacts 11, 12 and 13. In the elevation of the solenoid core, the hooked end 25 of the rod extension 24 of the core will contact with the under surface of the curved spring arm 37 causing the latter to yield when the hooked end 25 will pass above said arm 37 into position for a subsequent operation of the apparatus. That is to say, when the operating switch is moved to break the circuit, the weighted arm 29 will be tilted in an opposite direction because of the engagement of the hooked end 25 of the rod 24 with the upper surface of the spring arm 37. In this movement of the weighted arm 29 the spring arm contact member 33 will be moved out of engagement with the arm 34 as will be obvious, thereby breaking the circuit.

In Figure 3 of the drawings, I have illustrated in diagrammatic form, suitable electric connections for the various parts of the apparatus, and with more particular reference to this view of the drawings, the operation of the apparatus complete may be readily followed. Assuming that the motor 14 is running in one direction the current is flowing from the positive line through the contacts 18-19 to the contact member 5, through the switch from the contact 5 to the contact member 11, from the contact member 11 through the armature of the motor to the contact member 13, and from the contact member 13 through the switch to the contact member 7 and from the contact member 7 through the series field to the negative line. The current in the solenoid is flowing from the positive line to the contact member 6 and from 6 through the switch to the contact member 12, from 12 to the contact member 9, and from the contact member 9 through the solenoid winding and time device switch and resistance to the negative line. When throwing the switch from right to left hand position, the current will be broken between the contact points 6 and 12 and closed between points 6 and 9 which allows the solenoid core to drop, thereby opening the circuit at the point 18-19. In dropping, the core becomes engaged mechanically in the manner previously described with the arm 37 which is part of the common clock movement. This arm by moving the weighted arm 29 sets the clock mechanism in operation, at the same time because of the disengagement of the contact members 33 and 34

opening the circuit at this point. The clock movement after a predetermined time has elapsed, connects the circuit at 33—34 which completes the circuit through the solenoid 5 winding, from the positive line to contact 6, through switch from 6 to 9, from 9 through solenoid coil timing mechanism and desistance to the negative line. When the time device closes the circuit at 34, the core will 10 elevate, thereby closing the circuit at 18—19 which allows the current to flow from the positive line through 18—19 to the contact member 5; thence through the switch from the contact member 5 to contact member 8; 15 from 8 to contact member 13; and through the armature of the motor to contact member 11; thence from 11 to contact member 10, through switch to contact member 7 and from 7 through the series field to the negative line. It will be noted that the circuit is flowing in an opposite direction between the points 11 and 13 in this operation than in the previous one.

It is apparent that the present improvements may be readily applied to motor driven fans or the like, and when so applied, the operation is substantially automatic upon the shifting of the reversing switch lever. As distinguished from prior constructions, it is not necessary for the operator to time the reversing movement of the switch, or to provide stops for maintaining the switch in neutral position, but the operator may, by a quick and continuous movement shift the switch lever from circuit closing position to operate the motor in one direction to a reverse circuit closing position to operate the motor in an opposite direction without the possibility of 20 burning out the motor, and this is of especial advantage because the operation of the device may be left with impunity to an entirely inexperienced workman with little or no knowledge of electricity or the disastrous effect of quickly reversing a motor under the present practice.

By adjusting the stop 36, the length of the movement of the arm 29 may be adjusted at will, thereby timing the closing of 25 the circuit at 34 according to the time consumed in the stopping of the motor.

What is claimed is:—

1. In a device of the character described, the combination of a reversing switch for 30 an electric circuit, and time control means operatively associated with said switch whereby as the switch is moved into reversing position, the circuit will be closed to reverse the current, but not until after a 35 predetermined interval.

2. In a device of the character described, the combination of a reversing switch for an 40 electric circuit, suitable clock work mechanism operatively associated with the switch, 45 the movement of the clock mechanism being

governed by the actuation of the switch, and the clock mechanism having suitable electrical connections whereby to prevent closing of the circuit on the movement of the switch to reverse the current until the lapse 70 of a suitable interval of time.

3. In combination with a motor driven fan, of means for reversing the motor to convert the movement of the fan from a blower to a suction creating means including 75 a reversing switch electrically connected with the motor and movable in opposite directions, and a time control device operatively associated with the switch and operating when the switch is moved in either 80 direction to reversing position, to close the circuit only after the lapse of a predetermined interval.

4. In combination with a motor driven fan, of means for reversing the movement of 85 the fan including a switch operatively connected to the motor and adapted in one position to close the circuit to drive the motor in one direction and adapted in its other position to close the circuit and drive the motor in an opposite direction, and means operatively associated with the switch whereby reverse movements of the motor will be delayed for a predetermined interval after the movement of the switch to circuit closing 90 position.

5. In a device of the character described, the combination of a manually operated reversing switch for an electrical circuit, and operatively associated time controlled mechanism automatically operating as the switch is moved to circuit reversing position to prevent the immediate closing of the circuit and permitting the same to close the circuit only after the expiration of a predetermined 100 interval of time.

6. The combination with a motor, electric connections for imparting reverse movements thereto including a reversing switch mechanism operable at will and a time controlled 110 instrumentality interposed in said mechanism and acting to prevent closing of the circuit when the switch is moved to reversing position, and thereafter permitting closing of the circuit and thereby time the 115 reversing movement of said motor.

7. In combination with an electric motor, of electrically connected means for reversing the movement thereof including clock mechanism adapted to delay for a predetermined 120 interval the closing of the circuit in reversing the current whereby to permit the motor to gradually slow down prior to reversing the movement thereof.

8. In combination with an electric motor, 125 of electric connections for reversing the same, and clock mechanism operatively associated with said connections for retarding the reversal of the motor upon the movement of the switch to reversing position, 130

9. In combination with an electric motor, of electric connections for reversing the same including a switch, and clock mechanism operatively associated with said connections
- 5 for preventing reverse movement of the motor under the action of the switch until the lapse of a predetermined interval after movement of the switch to reversing position.
10. In combination, an electric motor, and
- 10 electrical connections for reversing the same including a time controlled switch permitting the motor to slow down before the circuit is closed under the action of said reversing means.
- 15 11. In combination, a motor, electrical connections therefor, an interposed switch for reversing the movement of the motor, and operatively associated clock mechanism preventing the closing of the circuit by the
- 20 movement of the switch for a time interval sufficient to cause the motor to first slow down.
12. The combination of a manually controlled switch lever, an electric circuit, and
- 25 a member to be operated thereby in reverse direction, and means interposed in the circuit for retarding the closing of the circuit after the switch is moved to circuit closing position, said means also operating to re-establish
- 30 the circuit to impart reverse movement of said member on the closing of the circuit.
13. The combination of a manually controlled switch lever, an electric circuit, and a member to be operated thereby in reverse
- 35 directions, and means interposed in the circuit for retarding the closing of the circuit after the switch is moved to circuit position, said means including a time controlled switch, said means operating to reverse the
- 40 current and impart reverse movement to said member on the closing of the circuit.
14. The combination of a manually controlled reversible switch lever, an electrical circuit, a movable member to be operated
- 45 thereby, and means interposed in the circuit for retarding the closing of the circuit after the switch has been moved into position to reverse the circuit and to reverse the movement of the said member, said means including a time controlled switch.
15. The combination of a manually controlled reversible switch, a reversible motor, an electric circuit for operating the latter, and means interposed in the circuit for retarding the closing of the circuit when the switch is moved to reversing position, whereby to allow the motor to first slow down, said means including a solenoid magnet and an electrically connected clock mechanism
- 55 having operative connection with the solenoid core to time the operation of the magnet switch to close the circuit.
16. In an appliance of the character described, the combination of a reversible
- 60 motor, a manually controlled reversing
- switch having electric connection for operating the motor, and time controlled means interposed between said switch and motor for timing the reversing movement of the motor after the switch has been moved to reversing position, whereby to prevent the destructive action on the motor by a sudden movement of the switch to reversing position.
17. In an appliance of the character described, the combination of a motor, a manually controlled reversing switch having electric connection with the motor, and means interposed between said switch and motor for timing the reversing movement thereof after the switch has been moved to circuit reversing position, said means comprising clock mechanism having a stationary contact member and a movable contact member, and a magnet switch adapted when energized to close the circuit when the contacts of the clock mechanism are in engagement.
18. In an appliance of the character described, the combination of a clock mechanism having a stationary contact member, a movable contact member, a rock arm support for the movable contact member, a solenoid switch having a core, and means establishing operative engagement between the core and arm whereby as the core is moved in one direction the rock arm will be moved to disengage said contacts, and whereby as the core is moved in an opposite direction, the clock mechanism will permit a timed reversing movement of the rock arm to engage said contacts and close the circuit.
19. In a time reversing switch, the combination of a ratchet wheel, a dog to impart movement thereto, a rock arm support for the dog, a contact member carried by the rock arm, a stationary contact member to be engaged by the movable contact member in one position of the latter to close the circuit, and an operatively associated magnet switch governed by the movement of the rock arm, whereby to close the circuit and reverse the current after the lapse of a time interval.
20. In a time reversing switch, the combination of a clock mechanism, a magnet switch controlled thereby, and a manually operable switch to open and close a circuit, and electrical connections between said switch, clock mechanism and magnet switch constructed and arranged whereby as the manually operated switch is moved into closed position to reverse the current, the resultant closing movement of the magnet switch is temporarily delayed by the clock mechanism.
21. In combination with a switch operable at the will of the operator for controlling the circuit for a motor or the like to impart reverse movements to the motor, of an inter-

posed time controlled mechanism including a stationary contact member, a movable contact member, a rock arm support for the movable member, time controlled means for 5 moving the rock arm support in one direction to cause engagement of the contact members to close the circuit at this point, and a magnet switch operatively associated with the arm to move the same in an opposite direction to disengage the contacts.

22. In a time reversing switch, the combination of a main reversing switch manually operable at will, a solenoid switch, a clock movement, the solenoid having a movable core adapted to become engaged mechanically to a part of the clock movement when the circuit is broken by the movement of the switch to reversing position whereby to set the clock movement in operation, said 20 clock movement having electrical contact members which when placed in engagement under the action of the clock movement will excite the solenoid coil to close its switch and thereby close the circuit.

23. In a time reversing switch, the combination of a part to be operated, an electric circuit therefor, a switch manually operable at will for opening and closing the circuit, and time controlled means interposed in the 30 circuit and operating to temporarily maintain the circuit open after the switch is moved to reverse circuit closing position.

24. In a time reversing switch, the combination of a part to be reversely operated, an electric circuit therefor, a switch manually operable at will for opening and closing the circuit, and time controlled means interposed 35 in the circuit and operating to temporarily maintain the circuit open for a predetermined interval after the switch has been moved to reversing position.

25. In a time reversing switch for fan motors, the combination of a reversible motor, a fan connected thereto and adapted

according to the movement of the motor to 45 constitute either a suction or blower element, an electric circuit to be connected to the motor, a switch manually operable at will for opening and closing the circuit, and means interposed in the circuit and operating 50 to temporarily maintain the circuit open after the switch is moved to circuit closing position to reverse the movement of the motor, said means being adjustable to vary the retarding of the time for closing the 55 circuit.

26. In combination with a motor driven fan adapted to be reversed whereby to change the same from a blower to a suction device or from a suction device to a blower, 60 electrical connections for the motor, a reversing switch manually controllable and operable at will, the said switch being adapted when moved to one position to close the circuit to the motor in one direction, and 65 when moved in another position to close the circuit in an opposite direction, and operatively associated time control mechanism acting to prevent closing of the circuit regardless of the position to which the switch is 70 moved until after a predetermined interval.

27. In combination with an electrical motor, of electric connections for reversing the same including a manually operable reversing switch, and clock mechanism operatively 75 associated with said connections for preventing the reverse movement of the motor regardless of the movement of the switch until after a predetermined interval subsequent to the movement of the switch to reversing 80 position.

In testimony whereof I hereunto affix my signature in the presence of two witnesses.

EDGAR P. HAZAZER.
